[57] **CLAIM**

The ornamental design for a foot positioning mat for x-ray patients, as shown and described.

DESCRIPTION

FIG. 1 is a top plan view of a foot positioning mat for x-ray patients showing my new design;

FIG. 2 is a side elevational view thereof, with all other elevational views being a mirror image thereof;

FIG. 3 is a bottom plan view thereof; and,

FIG. 4 is an enlarged side elevational view of the edge portion as seen from the lines 4—4 of FIG. 3.
